UNITED STATES PATENT OFFICE.

FREDERICK PHILLIP UHRIG AND CALVIN C. STRANGE, OF GALESBURG, ILLINOIS.

WASHING-MACHINE GEARING.

1,262,414.

Specification of Letters Patent. Patented Apr. 9, 1918.

Application filed February 9, 1917. Serial No. 147,562.

To all whom it may concern:

Be it known that we, FREDERICK P. UHRIG and CALVIN C. STRANGE, citizens of the United States, and residents of Galesburg, in the county of Knox and State of Illinois, have invented a new and Improved Washing-Machine Gearing, of which the following is a full, clear, and exact description.

10 This invention relates to a washing machine of that type having a wringer combined therewith and including mechanism whereby the washing machine or the wringer can be thrown into and out of operative connection with the driving motor.

15 The invention has for its general objects to improve and simplify the construction and operation of machines of the character referred to so as to be reliable and efficient 20 in use, comparatively simple and inexpensive to manufacture, and so designed as to be easily and quickly controlled.

A more specific object of the invention is the provision of a novel arrangement and 25 design of power transmitting means whereby the power can be thrown on or off to operate the washing machine agitator or the wringer, the wringer being so mounted that it can be thrown laterally to and from an 30 operative position with regard to the washing machine without, however, altering the driving connections with the wringer.

Still another object of the invention is to provide a simple, novel and effective means 35 for oscillating the agitator of the washing machine, part of the said means being associated with the hinge between the cover and body of the tub, whereby the cover can be opened and closed without altering the operative connections between the power transmitting mechanism and the agitator.

With such objects in view, and others which will appear as the description proceeds, the invention comprises various novel 45 features of construction and arrangement of parts which will be set forth with particularity in the following description and claims appended hereto.

In the accompanying drawings, which 50 illustrate one embodiment of the invention and wherein similar characters of reference indicate corresponding parts in all the views,

Figure 1 is a perspective view of the power driven washing machine and wringer,

the latter being shown in its inoperative 55 position;

Fig. 2 is a plan view of Fig. 1;

Fig. 3 is an enlarged vertical section on the line 3-3, Fig. 2, showing the transmission mechanism between the motor and washing machine and wringer;

Fig. 4 is an enlarged horizontal section;

Fig. 5 is a vertical section on the line 5-5, Fig. 4;

Fig. 6 is a detail sectional view on the 65 line 6-6, Fig. 4; and

Fig. 7 is a detail view showing the catch for holding the washing machine unclutched from the power transmitting mechanism.

Referring to the drawings, A designates 70 the washing machine, B the wringer, C the motor and D the transmitting mechanism. The tub 1 of the washing machine has at its top a rearwardly extending horizontal shelf 2 which supports the motor and the power 75 transmitting mechanism D, and on the casting of the latter is movably mounted the wringer B.

The cover 3 of the washing machine tub has hinge ears 4 through which passes a 80 pintle or rod 5 which also passes through hinge ears or lugs 6 fastened to the fixed part or shelf 2, whereby the cover can swing upwardly and backwardly to open position. The hinge ears or lugs 4 are formed of a 85 housing or plate 7 fastened to the top of the cover and serving to inclose part of the means for operating the agitator 8 of the washing machine. The agitator 8 has a vertical shaft 9 on which is a pinion 10 with 90 which meshes a segmental gear 11. This gear is pivoted at 12 on the top 3 of the washing machine and has an arm 13 extending rearwardly with its rear end connected by a link 14 with a sleeve 15 movable axially 95 on the pintle 5. The sleeve is reciprocated by means of a slide 16 which has spaced lugs 17 between which the sleeve is disposed, and these lugs are apertured so as to receive the pintle 5. By reciprocating the slide 16 the 100 agitator of the washing machine is oscillated.

The motor C transmits motion to the slide 16 through the mechanism D. This mechanism includes a vertical shaft 18 which carries at its lower end the crank arm 19 that is connected by a pitman 20 with the slide 16, so that as the crank arm rotates, the slide

- will be reciprocated. A speed reduction gearing 21 is operatively connected with a motor shaft 22 and the countershaft 23 of this gearing is connected through bevel gears 24 and 24' with the vertical shaft 18. The gearing 21 and shaft 18 are housed in a stationary casing 25 mounted on the shelf 2, there being suitable bearings in the housing for the rotating parts. The crank arm 19 is loose on the lower end of the shaft 18 and is adapted to be connected therewith by a clutch 26 feathered on the shaft 18, and a forked lever 27 is connected with this clutch 26 to throw it into or out of operative position. The lever is fulcrumed at 28 on the casing 25 and has an upwardly extending handle 29 which is engageable with a catch 30 on the outside of the casing, as shown in Fig. 7, when the clutch is to be held in disengaged position. When the handle of the lever is released from the catch, the clutch element 26 by its own weight will be maintained in engagement with the crank 19, so as to operate the washer.
- 25 The wringer B is of any approved construction, and the side members 31 have their lower bifurcated ends straddling a horizontal arm 32 to which the feet 33 of the members 31 are fastened by means of angles 34. The inner end of the arm 32 is vertically adjustable on a bracket 35 which has a vertical groove 36 into which engages a tongue 37, as shown in Fig. 4, and a bolt 38 passes through the bracket 35 and through a vertical slot 39 in the arm. The bracket is carried by a horizontal ring 40 which is rotatable around a neck 41 on the top of the casing 35, and a key 42 on the ring 40 engages in an annular groove 43, whereby the ring is rotatably held in place. By this means the wringer can be swung on a vertical axis or around the shaft 18 as a center. The ring is held in different positions by means of a locking member 44 which is slidable in a lug 45 in the outer end of the arm 32, and in the bottom of the bracket 35 and on the external surface of the casing 25 are notches 46 into which the inner end of the locking pin or rod can be engaged to lock the wringer in the operative position shown in Fig. 4, or in the inoperative position shown in Fig. 2. The locking pin is held in engaged position by a spring 47.
- 50 Power is applied to the rolls of the wringer by the lower roll 48 having a shaft 49 extended beyond the frame of the wringer, and feathered on this shaft are opposed bevel gears 50 and 51 adapted to engage one at a time with the bevel gear 52 on the upper end of the shaft 18, as shown in Fig. 3. This gearing is inclosed in a casing 53 and out of the top of the casing projects a lever 54 fulcrumed on a pin 55, and the lower end of the lever is connected at 56
- with a sleeve 57 to which the gears 50 and 51 are connected, the sleeve being feathered on the shaft 49. When both gears 50 and 51 are out of engagement with the gear 52 the wringer is idle, but when the gear 50 or 51 is meshing with the gear 52, the wringer roll will be turned in one direction on the other. The gear casing 53 is mounted on the ring 40 so as to turn with the wringer as the latter is swung to and from its operative position.
- 55 On the tub 1 is a drain-board 60 over which the wringer is positioned when in use, whereby the water running from the clothes will drain back into the tub.
- 60 From the foregoing description taken in connection with the accompanying drawings, the advantages of the construction and method of operation will be readily understood by those skilled in the art to which the invention appertains, and while we have described the principle of operation, together with the machine which we now consider to be the best embodiment thereof, we desire to have it understood that the machine shown is merely illustrative and such changes may be made when desired as fall within the scope of the appended claims.
- Having thus described our invention, we claim as new and desire to secure by Letters Patent:
1. A mechanism for operating a washing machine or wringer comprising, a casing, an upright shaft therein, a crank on the lower end of the shaft, a connecting rod operated by the crank, a clutch connecting the crank with the shaft, a motor, a power multiplying gear between the motor and shaft and mounted in the casing, a second casing rotatably mounted on the first, a horizontal shaft in the second casing and disposed above the first mentioned shaft, a gear on the first mentioned shaft, and a gear on the second mentioned shaft and movable into and out of engagement with the last mentioned gear.
- 105 2. A mechanism for operating a washing machine or wringer comprising a casing, an upright shaft therein, a crank on the lower end of the shaft, a connecting rod operated by the crank, a clutch connecting the crank with the shaft, a motor, a power multiplying gear between the motor and shaft and mounted in the casing, a second casing rotatably mounted on the first, a horizontal shaft in the second casing and disposed above the first mentioned shaft, a gear on the first mentioned shaft, a bracket passing to the second casing and rotatably mounted on the first casing, and interengaging means between the bracket and first casing for holding the bracket on the latter.
- 110 3. A mechanism for operating a washing machine or wringer, comprising a support-

ing structure including a casing, a shaft mounted in the structure and extending through the casing, with the ends projecting, an element on one end of the shaft, a clutch 5 for connecting the element with the shaft for actuation thereby, a power multiplying gearing in the casing and operatively connected with the shaft, a second casing into

which the shaft extends and rotatably mounted on the first casing, a second shaft 10 extending into the second casing, and a reversible gearing for operatively connecting the shafts or for disconnecting the shafts.

FREDERICK PHILLIP UHRIG.
CALVIN C. STRANGE.
